UNITED STATES PATENT OFFICE

VERNIE A. FOX, OF DETROIT, MICHIGAN, ASSIGNOR TO YOUNG BROTHERS COMPANY, OF DETROIT, MICHIGAN, A CORPORATION OF MICHIGAN

AIR-CIRCULATION SYSTEM FOR OVENS

Application filed June 22, 1928. Serial No. 287,523.

The present invention pertains to a novel oven of the type in which a conveyor carries a number of metal plates which have been enameled, painted, japanned or otherwise treated and which require drying.

In the particular oven constituting the subject matter of the invention, a stream of air is caused to circulate in the direction opposite to that of the conveyor. It is the object of the invention to effect the circulation of air in such a manner that the entering plates are first heated by the exhausting air, then passed through the hotter zone of the oven, and finally through a cooling zone prior to being taken out of the oven. This arrangement utilizes the heat in the air to a satisfactory degree and permits the dried plates to be discharged from the oven in a condition suitable for handling.

20 The invention is fully disclosed by way of example in the following description and in the accompanying drawing, in which—

Figure 1 is a vertical section of an oven constructed according to the invention;

25 Fig. 2 is a vertical section at right angles to Figure 1; and

Fig. 3 is a detail section in a plane parallel to that of Figure 1, showing the construction of the conveyor.

30 Reference to these views will now be made by use of like characters which are employed to designate corresponding parts throughout.

The body of the oven consists of a vertical and hollow column 1 having a loading opening 2 in one wall thereof, at the bottom, and an unloading opening 3 in the opposite wall and also at the bottom. In the top of the oven is journaled a shaft 4 carrying an exterior gear 5 by means of which it is driven. Within the oven, the shaft carries a pair of sprocket wheels 6 close to the side walls. At the base of the oven, and exteriorly thereof, are provided a pair of upright bearings 7 contiguous to opposite walls and aligned to support a shaft 8 parallel to the shaft 4. The bearing holes 9 are elongated in the vertical direction, and so are the slots 10 in the side walls through

5 which the shaft passes, so that the distance between the shafts 4 and 8 is permitted to vary as pointed out more in detail below. The shaft 8 carries a pair of sprocket wheels 11 in line with the wheels 6 on the shaft 4. Each pair of aligned sprocket wheels is 55 trained by a sprocket chain 12.

Each chain consists of double links 13 connected by pins 14 in the usual manner. Certain of these pins at intervals are slightly extended inwardly of the oven as indicated 60 by the numeral 15 in Figure 2. Fingers 16 are suspended from the extensions by means of integral bosses 17 receiving such extensions. Each pair of opposed fingers 16 supports a stirrup or cradle 18 depending therefrom and attached thereto by rivets 19. The stirrup is completed by transverse bars 20 secured to the base portion thereof as shown more clearly in Figure 3. The coated plates to be dried are entered into the oven through 70 the opening 2 and erected upon the bars 20 which maintain a horizontal position throughout the entire course of the endless conveyor. The shaft 4 is driven in a manner to turn the wheels 6 and 11 in the clockwise direction as viewed in Figure 1, so that the ascending side of the conveyor rises from the work inlet 2 and the other side descends towards the work outlet 3. The latter opening is also used for admission of air into the 75 oven.

A heating element 21 of any desired or suitable character is mounted in the oven slightly above the shaft 8. Above the work inlet 2, the oven wall is formed with an air exhaust port 22 connected to a suction fan 23 by a pipe 24. In order to prevent withdrawal of hot air directly from the heating element through the port 22 without reaching the upper part of the oven, a baffle plate 85 25 is arranged between the heating element and the ascending side of the conveyor. This member extends to substantially the top of the oven and is bent under the heating element as indicated by the numeral 26. 90 The baffle system is completed by a guard 27 extending from a point opposite the air intake 3 to a point somewhat above the top of the heating element. The guard is positioned between the heating element and 100

the descending side of the conveyor and contacts with the portion 26 in order to obstruct a direct path from the heating element to the port 22. The disposition of the 5 lower part of the guard opposite the air intake 3 reduces the flow path between the air intake and the port 22, although the edges of this lower portion of the guard are cut out at 28 to accommodate the wheels 10 11. Both plates 25 and 27 have their edges supported in opposite walls of the body 1.

The action of the suction fan 23 produces a current of fresh air entering the oven through the intake 3. This air is substantially 15 cool while rising along the guard 27 and is heated after passing the top of the guard. The fan causes this stream to travel over the top of the baffle 25 and down to the exhaust port 22.

20 The work which is admitted through the opening 2 rises through this descending stream of hot air and is in this way pre-heated before coming to the hotter zones at the opposite side of the baffle 25. After having 25 passed the upper edge of the guard 27 on the descending side of the conveyor, the work has been sufficiently heated and now enters the cooler zone directly adjacent the guard 27. Consequently the work is without 30 drawn through the opening 3 in a cooled condition which facilitates handling and dispenses with supplementary cooling equipment.

Although a specific embodiment of the 35 invention has been illustrated and described, it will be understood that various alterations in the details of construction may be made without departing from the scope of the invention as indicated by the appended claims.

40 What I claim is:—

1. In an oven, a vertically moving conveyor, a work inlet and a work outlet at the bottom of the oven and at the ascending and descending sides respectively of the conveyor, air inlet means at the work outlet and air exhaust means at the opposite wall of the oven, a heat source in said oven, a baffle partitioning the heat exchange area of said source from said exhaust means, and a guard 45 partitioning the heat exchange area of said heat source from the descending side of the conveyor to provide a cooling zone at said work outlet.

2. In an oven, a vertically moving conveyor, a work inlet and a work outlet at the bottom of the oven and at the ascending and descending sides respectively of the conveyor, air inlet means at the work outlet and air exhaust means at the opposite wall 50 of the oven, a heat source in said oven, a guard partitioning the heat exchange area of said heat source from the descending side of the conveyor to provide a cooling zone at said work outlet, and a baffle between 55 said heat exchange area and air exhaust

means and extending beneath said heat source into engagement with said guard.

3. In an oven, a vertically moving conveyor, work inlet and air exhaust means in the bottom of said oven at the ascending side of 70 said conveyor, work outlet and air inlet means at the descending side of said conveyor, a heat source in said oven, a baffle partitioning the heat exchange area of said source from said exhaust means, and a guard 75 partitioning the heat exchange area of said heat source from the descending side of the conveyor to provide a cooling zone at said work outlet.

4. In an oven, a vertically moving conveyor, work inlet and air exhaust means in the bottom of said oven at the ascending side of said conveyor, work outlet and air inlet means at the descending side of said conveyor, a heat source in said oven, a guard 80 partitioning the heat exchange area of said heat source from the descending side of the conveyor to provide a cooling zone at said work outlet, and a baffle between said heat 85 exchange area and air exhaust means and extending beneath said heat source into engagement with said guard.

In testimony whereof I affix my signature.
